CASING FOR DUPLICATING MACHINES

Luis Mestre, New York, N. Y., assignor to Style
Duplicator Corporation, New York, N. Y., a cor-
poration of Delaware

Application August 14, 1939, Serial No. 290,102

7 Claims. (Cl. 101—116)

This invention relates to casings for rotary duplicating machines of that class in which a perforated cylinder is employed, adapted to support a stencil sheet on its periphery and including 5 means for rotating the cylinder to bring the surface of the stencil into contact with sheets of paper passing between the cylinder and a pressure roll.

An object of the invention is to provide a casing 10 for such a machine which will completely enclose the main operating parts thereof and of which the sheet receiving and sheet delivery trays themselves form a part.

A further object of the invention is to provide 15 a casing in which the top portion is hinged to one of the side members and may be folded back to permit access to the interior of the casing but which is provided with a flat surface which may be used to assemble the sheets to be printed upon.

20 It has heretofore been proposed to provide sheet receiving and delivery trays which may be folded up but in the constructions with which I am aware, these trays do not themselves constitute any portion of the casing, but according to 25 such constructions, it is proposed that a separate casing be placed over the machine after the trays have been folded up.

According to the present invention, the trays 30 form part of the casing and with the permanent side members and the top thereof, form a complete closure for the operative parts of the machine, except the operating handle and some control knobs which project through one of the side walls of the casing. The top of the casing over- 35 laps the upper edges of the trays when these trays are folded up and the trays themselves as well as the top, fit into recesses formed by the side frames of the machine in cooperation with facing strips, so that when the casing is closed, 40 a substantially dust-proof construction is provided. The details of construction will be better understood by reference to the accompanying drawings, in which:

Figure 1 is a perspective view of the machine 45 with the casing closed;

Figure 2 is a perspective view on a larger scale with the sheet receiving and delivery trays opened up to operative position and with the top of the casing folded back;

50 Figure 3 is a section on the line 3—3 of Figure 1; and

Figure 4 is a section on the line 4—4 of Figure 3.

Since duplicating machines of the general type to which my invention is applicable are well 55 known, it will be necessary only briefly to refer

to the usual operative parts constituting a machine of this type.

Referring to Figure 3, the operative parts of the machine are supported by side frames, each of which comprises a base member 2 having a flat 5 upper face 4 and sloping side faces 5. Horizontal and vertical cross members 6 and 7 give the required rigidity to the frame and the two frames are tied together by a U-shaped bar 8, a portion of which is also shown in Figure 2. Supported 10 by the side frames is a shaft 9 carrying a perforated stencil cylinder 10 which may be rotated by the usual handle 11. A pressure roller 12, Figures 3 and 4 is provided between which and the stencil carried by the stencil roller 10, the sheet to 15 be printed upon is fed.

For supporting and feeding the sheets, a sheet delivery tray is provided. This tray is preferably made in two parts, the portion 13, Figure 3, being stationary. The second portion 14 is hinged at 20 15 to the stationary portion 13. This tray carries side guides 16 for holding the sheets of paper in proper position and the sheets may be fed in any suitable manner to the stencil cylinder and pressure roller. In the particular embodiment 25 shown, feed rollers 18 are shown as supported on a rocking frame having side members 20 and a connecting bar 21. A link 17, a portion of which is shown in Figure 3, may be connected to the cylinder in known manner to cause rocking of 30 the frame and consequent feeding of the sheets, one at a time.

In Figure 2 the portion 14 of the tray is shown in operative position wherein this portion aligns with the fixed portion 13, while in Figure 3, the 35 portion 14 is shown as having been folded up.

A sheet delivery tray 22 is hinged to the side frames at 24, Figures 3 and 4 and is held in its horizontal position shown in Figure 2 by a stop 25. A sheet stop 26 is also provided which has a pin 40 and slot connection with the tray 22 and a hinge portion 28 which may be folded down into the position shown in Figure 3 prior to the folding up of tray 22 to the position shown in Figure 3. Side guides 30 are suitably secured to the tray 22 45 and are spaced from the edges thereof in order that the tray when folded up may fit into recesses to be immediately described.

The sloping sides and flat top of each of the frames is partly covered by a facing strip 32, 50 Figures 1, 2 and 4. These facing strips, as particularly shown in Figure 4, overlap the outside edges of the frame faces to form a notch 33 into which the upper edges of the plates 34 fit. These plates constitute the permanent sides of the 55

casing. The strips 32, however, stop short of the inner edges of the side frames thereby forming shoulders 35 and the space between opposite shoulders constitute recesses into which the trays 5 fit when folded up, the trays lying along the face of the frames and within the recesses. The trays constitute the ends of the casing when in folded-up position.

It has previously been stated that the guides 10 30 are spaced from the edges of the tray 22 and the purpose of this spacing is two-fold; first to make it possible for the guides 30 to be entirely within the contour of the frame members, and second to provide a surface which may lie against 15 the sloping faces of the frame members when the tray 22 is folded up.

Hinged to one of the facing strips as at 36, Figures 1 and 2, is a casing top having a flat surface 38 and sloping sides 40. This top is 20 hinged at one edge to a facing strip as clearly shown in Figure 2 and when folded over to the position shown in Figure 1, its opposite edge rests in the recess formed by the facing strip 32 and the opposite frame member. The sloping edges 40 25 overlap the top edges of the trays 14 and 22 when the latter are folded up to the position shown in Figures 1 and 3, thereby forming a complete closure.

The portion 14 of the sheet delivery tray is 30 supported in its horizontal position by links 42 and 44, the latter being suitably slotted and connected by pins to the side frames in order to permit the hinged portion 14 of the tray to be folded upwardly.

35 The side guides for the paper are made in two parts, the part 16 being pivoted to the part 19. This latter portion of each guide is adjustable along a slot 23, as is usual in machines of this character.

40 When the machine is in use, the trays are opened up as in Figure 2. The top, however, may either be folded back as in Figure 2 or may be folded over into the position shown in Figure 1 while the trays are in the Figure 2 position.

45 When so positioned, the flat portion of the top provides a convenient surface upon which the sheets to be printed upon may be assembled and aligned.

What I claim is:

1. A casing for a duplicating machine having 50 a cylinder and pressure roll, together with a sheet delivery and a sheet receiving tray, said casing having side members supporting said cylinder and roll, said trays foldable to form the end members of the casing and a top hinged to one of said side members and foldable to position to cooperate with and overlap the upper edges of said trays when the latter are in folded position.

2. A casing for a duplicating machine having 60 parallel side members for supporting the operative parts of the machine, said members having a straight upper edge, a top hinged to one of said side members and cooperating with the other side member when in closed position and providing a level surface upon which the sheets to be printed upon may conveniently be assembled.

65 3. A casing for a duplicating machine having a base and side members for supporting the operating parts of the machine, said side members

having a flat upper edge with sloping sides, a sheet receiving and a sheet delivering tray, each hinged within the casing and when folded up conforming to the contour of the sloping sides of said members, and a top hinged to one of said side members and cooperating with the other side member and with said tray portions when the latter are folded up, to form a complete closure. 5

4. A casing for a duplicating machine having parallel side members for supporting the operative parts of the machine, said members having a straight upper edge, a top having a flat portion and hinged to one of said side members and cooperating with the other side members when in closed position and providing a level surface upon 10 which the sheets may conveniently be aligned, a sheet delivery and a sheet receiving tray each hinged within the casing, said trays when folded up cooperating with the side members and said top to form a complete closure. 15

5. In a duplicating machine having side frames for supporting the operative parts of the machine, said frames each having a flat upper face and sloping lateral faces, a casing for said machine including facing strips, said strips overlying the 20 outer edges of the frame faces but stopping short of the inner edges thereof thereby forming shoulders, the space between the shoulders constituting recesses, foldable sheet delivery and sheet receiving trays adapted in folded position to lie 30 against the frames along the sloping faces thereof and fitting into said recesses.

6. In a duplicating machine having side frames for supporting the operative parts of the machine, said frames each having a flat upper face and 35 sloping lateral faces, a casing for said machine including facing strips, said strips overlying the outer edges of the frame faces but stopping short of the inner edges thereof thereby forming shoulders the space between the shoulders constituting 40 recesses, foldable sheet delivery and sheet receiving trays adapted in folded position to lie against the frames along the sloping faces thereof and fitting into said recesses, and a top hinged at one edge to one of said facing strips, the opposite 45 edge of said top when folded over fitting into the recess between the opposite frame and its facing strip, the sides of said top overlapping the folded-up trays.

7. In a duplicating machine having side frames 50 for supporting the operative parts of the machine, said frames each having a flat upper face and sloping lateral faces, a casing for said machine including facing strips, said strips overlying the outer edges of the frame faces but 55 stopping short of the inner edge thereof thereby forming shoulders, the space between the shoulders constituting recesses, foldable sheet delivery and sheet receiving trays adapted in folded position to lie against the frames along the sloping 60 faces thereof and fitting into said recesses, and a top having a flat surface and slightly rounded sides hinged at one edge to one of said facing strips, the opposite edge of said top when folded over fitting into the recess between the opposite 65 frame and its facing strip, its rounded sides overlapping the folded-up trays.

LUIS MESTRE.
